COMBINED AND PERPETUAL INDICATOR
OF THE MENSTRUAL CYCLES

Joseph Spielmann, Paris, France

Application December 11, 1946, Serial No. 715,521
In France October 1946

9 Claims. (Cl. 235—89)

1

My present invention relates to a catamenial calendar and, in particular to a continuous catamenial calendar for determining the date and length of the menstrual periods.

It is an object of my present invention to provide a calendar of this type on which the different lengths of menstrual periods are indicated in accordance with specific dates for which the calendar can be set.

It is another object of my present invention to provide a calendar of the type indicated which permits ascertainment of the dates of the next following menstruation period after ascertainment of the lengths of the menstrual intervals in case of a specific individual.

A still further object is to provide a calendar which, in addition to the above objects also permits a reading of the period of fertility.

Another object of my invention is to provide a calendar which permits reading of the items indicated as adjusted to different menstrual cycles.

A still further object of my invention is a calendar which is adapted to perform the functions indicated for a month of any possible length, i. e. including the month of February in regular, and in leap years.

With the above objects in view, my present invention mainly consists in a continuous calendar comprising an envelope being open at opposite ends, a slide member movable therethrough, tables of information provided on said slide member, the said tables being arranged so that each side of the slide member contains two distinct tables, and the two distinct tables are arranged inversely in the direction from top to bottom of the slide member whereby the tables may be used for four types of months according to the number of days in each month.

A particularly preferred embodiment of my invention is to have a continuous catamenial calendar comprising an envelope being open at opposite ends, a slide member movable therethrough, tables of information provided on the slide member, the tables being arranged so that each side of the slide member contains two distinct tables, the two distinct tables being arranged inversely in the direction from top to bottom of the slide member whereby the tables may be used for four types of months according to the number of days in each month, a first series of numbers forming part of the tables and representing all of the days of the month, a plurality of superimposed second series of numbers forming part of said tables and each representing specific

2

days of a month, a plurality of superimposed numerals provided on said envelope and each representing a different length of the menstrual cycle, a plurality of windows formed in the envelope and arranged in relation to the series of numbers so that when a particular day of the first series appears in a first one of the windows indicating the first day of an earlier menstruation, an individual day of said second series will appear on the level of the cycle indicating numerals in a second display window indicating the first day of a following menstruation according to the specific cycle, and a series of days will appear in a third group of display windows on the level of each of the cycle indicating numerals, the latter display windows indicating the corresponding period of fertility.

The novel features which I consider characteristic for my invention are set forth in particular in the appended claims. The invention itself however, both as to its construction and its method of operation, together with additional objects and advantages thereof, will be best understood from the following description of specific embodiments when read in connection with the accompanying drawings, in which:

Fig. 1 is a plan view of the front side of the slide member employed in the calendar according to my present invention;

Fig. 2 is a plan view of the front side of the envelope in which the slide is movable;

Fig. 3 is a plan view of the reverse side of the slide member; and

Fig. 4 is a plan view of the reverse side of the envelope.

Referring to the drawings, it will be seen that a slide member generally indicated by T and having a flat rectangular shape is movable in an envelope generally indicated by E, and having a shape identical with that of the slide member. The envelope is open at its short ends so that the slide member can move lengthwise therethrough.

Each side of the slide member and each side of the envelope carries items of information. The reference letters used in the following to indicate these items in the drawings will be identical to the two sides of the slide member and for the two sides of the envelope except that in each case the reverse side will be indicated by a prime symbol.

In addition, similar information appears on one and the same side of the slide member in alternate rows and inverse position that the slide member may be reversed in the envelope to per-

mit reading of a corresponding type of information. The slide member is thus provided with four tables of information, two appearing in alternate rows and in relatively inverted form on the front sheet, and two appearing in the same manner on the reverse side.

The front side of the slide member in the embodiment shown carries the information read from the top to the bottom relating to months having 31 days, and when read from bottom to top shows information relating to months having 29 days. The reverse side carries information relating to months having 28 and 30 days. The various tables may be readily identified by the large numerals shown in the drawings, and indicated by the reference letters *d*, *e*, *d'* and *e'*.

In describing the individual items appearing in each of the four tables, it will be noted that there are several series of numbers which for convenience in the drawings have been represented only by the first and last few numbers of each series, omitting the intermediate numbers.

In the marginal portion of each table designated *f*, *g*, *f'* and *g'*, different sets of identical numbers, i.e. either 31 or 29, or 28 or 30 appear for general indication of the number of days in a particular month. Each number is repeated a suitable number of times, corresponding to the days existing in that month, e.g., the 31 at the top of the table in Figure 1, would be repeated 31 times.

Beneath these figures, a series of first consecutive numbers, *m*, *n*, *m'* and *n'* appear, this series running from one up to the number corresponding to the maximum number of days in the respective months. These numbers are intended to represent the specific day in an earlier month on which a specific menstruation has begun, as will be further explained below.

In the area enclosed by the line *a*, *a'*, a second series of numbers in the form of a plurality of horizontal rows of numbers *o*, *p*, *o'* and *p'*, is shown, which in the use of the table represents the dates of the next menstruation, and corresponding periods of fertility. In some cases these numbers will run into a following month as indicated at *b*, *b'*, and the dates of the following months may then be distinguished by a different color or otherwise, e.g. a different color of background.

The envelope *E* which is shown in Figures 2 and 4, and in which the slide member is movable has a recess at either of its short sides, the recess being indicated as *c*, *c'*. In addition, the envelope is provided with windows *h*, *h'*, *i*, *i'* and *l*, *l'*. The purpose of these windows *h*, *h'* is to make visible the figures in portions *f*, *g*, *f'* and *g'* of the slide member and individual figures of the series *m*, *n*, *m'* and *n'*.

The purpose of the windows *i* and *l* is to make visible different items of series *o*, *o'*, *p*, *p'*. This will be explained at a later point.

On the envelope itself there is a vertical column of figures counting from 24 to 32 as indicated at *k*, *k'*, which is correlated to the items appearing in windows *i*, *i'*, *l*, *l'* by arrows *j*, *j'*.

In addition to exposing the number of days in a particular month, the slots *c* and *c'* also facilitate the manipulation of the slide member in its movement relative to the envelope.

One method of use which will now be described enables information to be obtained about the length of the menstruation cycle, i.e. the number of days which passes from the first day of one menstruation until the day preceding the next

menstruation. The procedure in this case is as follows:

- Having noted the date of the beginning of one menstruation and that of the next, the slide member is engaged in the envelope so that the number of days in the month in question appears in the slot *c* or *c'*; one side of the instrument being reserved for months of 31 and 30 days, the other side for months of 29 and 28 days.
- 10 The slide member is then slid until there appears in the window *h* or *h'* of the envelope, the date of the beginning of the first menstruation. At the top of the window appears one of the indications of the number of days of the month on the strips *f*, *f'* or *g*, at the bottom the day of the month.

Then, the date of arrival of the next menstruation already noted is looked for in one of the windows *i* and *i'* and, by following an arrow *i* or *j'*, the length of the cycle is read on the length-of-cycle index *k* or *k'*.

Taking Figure 2 as an example, the window *h* shows day 4 of a month of 31 days. If the date of arrival of the next menstruation is shown as the 29th, the index *k* tells us that the length of the cycle is 28 days. Obviously, the operation must be repeated for several cycles if exact information is desired. Allowing for the variations which normally occur, it can therefore be ascertained whether there is complete irregularity. Thus, it will be known when medical attention should be sought.

If the cycles are regular, no matter whether they are simple, that is, always the same, or multiform, that is, varying within certain foreseeable limits, only, data are provided which enable other uses of the indicator to be made.

The methodical work of Doctors Ogino and Knaus has shown that the genetic period or period of fertility, that is the five days of ovulation plus the three "survival" days, lies between the 12th and 19th days before menstruation. Thus, the indicator permits determining of this period also. This knowledge is indispensable. It is relied on to select or put off the moment which appears favorable for procreation (and for confinement) for family, health or eugenic reasons.

If the cycles are regular and simple, it is only necessary, as soon as the first day of a menstruation arrives, to set the date to appear in the window *h* or *h'*, to proceed as shown above, and to read off the genetic period through one of the windows *l* or *l'* opposite the corresponding length-of-cycle index.

If the cycles are regular, but multiform, the reading of the periods appearing through the windows *l* and *l'* opposite the corresponding length-of-cycle index is combined. All the dates determined in this way form part of the genetic period, taking account of the differences in the length of the cycles.

Furthermore, the windows *i* and *i'*, opposite the length-of-cycle index or indices, indicate, according to the case, the probable date or dates of arrival of the next menstruation.

Figure 4, for example, shows in the window *h*, the numeral 4 of a month of 28 days, that is the normal February. If the length of the cycles varies between 24 and 32 days the numbers appearing in all the windows *l* indicate the next genetic period augmented by the margin of time due to the variation, say from the 9th to the 24th February. In the same way, the window *i* shows the possible dates of arrival of the next menstruation, say 28th February to 8th March, the March

dates appearing at the bottom in a different color, reserved for the dates of the following month. It is obvious that an extreme theoretical case is now being considered.

In practice, it is only necessary to refer to the row or rows of genetic period numbers corresponding to one or several of the length-of-cycle indices. Thus, if the cycles are regular cycles of 30 days, the results read opposite the index 30 give a genetic period running from the 15th to the 22nd February, with the next menstruation for the 6th March.

The position of the slide member in the envelope is reversed as necessary. The instrument shown is provided for cycles varying from 24 to 32 days. But, obviously, modifications may be made in the number and length of the cycles shown.

The instrument may advantageously be made of any of the synthetic resin materials usually called "plastics", or it may be made of metal or of cardboard or the like.

Clearly it may be made with variations in construction which do not affect the principle on which it is based.

The blank parts of the slide member and the envelope are intended for any relevant instructions.

If consulted in a reasonable way, the instrument is a certain and precise guide for women and a valuable aid for the gynaecological physician.

It will be understood that each of the elements described above, or two or more together, may also find a useful application in other types of catamenial calendars, differing from the types described above.

While I have illustrated and described the invention as embodied in a continuous catamenial calendar, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications, without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desire to secure by Letters Patent is:

1. A continuous calendar comprising an envelope being open at opposite ends; a slide member movable therethrough; a plurality of windows formed in said envelope; tables of information provided on said slide member, individual items of said tables being visible through said windows of said envelope, the said tables being arranged so that each side of said slide member contains two distinct tables, and the said two distinct tables being arranged inversely in the direction from top to bottom of the slide member whereby the tables may be used for four types of months according to the number of days in each month.

2. A continuous catamenial calendar comprising an envelope being open at opposite ends; a slide member movable therethrough; tables of information provided on said slide member, the said tables being arranged so that each side of said slide member contains two distinct tables,

the said two distinct tables being arranged inversely in the direction from top to bottom of the slide member whereby the tables may be used for four types of months according to the number of days in each month; a first series of numbers forming part of each of said tables and representing all of the days of said month; a second series of numbers forming part of each of said tables and representing specific days of a month; and a plurality of windows formed in said envelope and arranged in relation to said series of numbers so that when an individual day of said first series is visible in a first window, indicating the first day of an earlier menstruation an individual day of said second series will appear in a second window indicating the first day of a next menstruation.

3. A continuous catamenial calendar comprising an envelope being open at opposite ends; a slide member movable therethrough; tables of information provided on said slide members, the said tables being arranged so that each side of said slide member contains two distinct tables; the said two distinct tables being arranged inversely in the direction from top to bottom of the slide member whereby the tables may be used for four types of months according to the number of days in each month; a first series of numbers forming part of each of said tables and representing all of the days of said month; a plurality of superimposed second series of numbers forming part of each of said tables and each representing specific days of a month; a plurality of superimposed numerals provided on said envelope and each representing a different length of menstrual cycle; and a plurality of windows formed in said envelope and arranged in relation to said series of numbers so that when a particular day of said first series appears in a first one of said windows indicating the first day of an earlier menstruation an individual day of said second series will appear on the level of each of said cycle indicating numerals in a second window indicating the first day of a following menstruation according to the specific cycle.

4. A continuous catamenial calendar comprising an envelope being open at opposite ends; a slide member movable therethrough; tables of information provided on said slide member, the said tables being arranged so that each side of said slide member contains two distinct tables, the said two distinct tables being arranged inversely in the direction from top to bottom of the slide member whereby the tables may be used for four types of months according to the number of days in each month; a first series of numbers forming part of each of said tables and representing all of the days of said month; a second series of numbers forming part of each of said tables and representing specific days of a month; and a plurality of windows formed in said envelope and arranged in relation to said series of numbers so that when an individual day of said first series is visible in a first window, indicating the first day of an earlier menstruation, an individual day of said second series will appear in a second window indicating the first day of a next menstruation, and a series of days will appear in a third display window indicating the corresponding period of fertility.

5. A continuous catamenial calendar comprising an envelope being open at opposite ends; a slide member movable therethrough; tables of information provided on said slide member, the said tables being arranged so that each side of

said slide member contains two distinct tables, the said two distinct tables being arranged inversely in the direction from top to bottom of the slide member whereby the tables may be used for four types of months according to the number of days in each month; a first series of numbers forming part of each of said tables and representing all of the days of said month; a plurality of superimposed second series of numbers forming part of each of said tables and each representing specific days of a month; a plurality of superimposed numerals provided on said envelope and each representing a different length of menstrual cycle; and a plurality of windows formed in said envelope and arranged in relation to said series of numbers so that when a particular day of said first series appears in a first one of said windows indicating the first day of an earlier menstruation an individual day of said second series will appear on the level of each of said cycle indicating numerals in a second window indicating the first day of a following menstruation according to the specific cycle, and a series of days will appear in a third group of windows on the level of each of said cycle indicating numerals, the latter windows indicating the corresponding period of fertility.

6. A continuous catamenial calendar comprising an envelope being open at opposite ends; a slide member movable therethrough; tables of information provided on said slide member, the said tables being arranged so that each side of said slide member contains two distinct tables, the said two distinct tables being arranged inversely in the direction from top to bottom of the slide member whereby the tables may be used for four types of months according to the number of days in each month; a first series of numbers forming part of each of said tables and representing all of the days of said month; a second series of numbers forming part of each of said tables and representing specific days of a month; a plurality of windows formed in said envelope and arranged in relation to said series of numbers so that when an individual day of said first series is visible in a first window, indicating the first day of an earlier menstruation, an individual day of said second series will appear in a second window indicating the first day of a next menstruation; and means for indicating the type of month associated with each table, the latter means being provided on said slide member.

7. A continuous catamenial calendar comprising an envelope being open at opposite ends; a slide member movable therethrough; tables of information provided on said slide member, the said tables being arranged so that each side of said slide member contains two distinct tables, the said two distinct tables being arranged inversely to the direction from top to bottom of the slide member whereby the tables may be used for four types of months according to the number of days in each month; a first series of numbers forming part of each of said tables and representing all of the days of said month; a second series of numbers forming part of each of said tables and representing specific days of a month; a plurality of windows formed in said envelope and arranged in relation to said series of numbers so that when an individual day of said first series is visible in a first window, indicating the first day of an earlier menstruation, an individual day of said second series will appear in a second window indicating the first day of a

next menstruation; means for indicating the type of month associated with each table, the latter means being provided on said slide member; and a recess provided in said envelope for making visible said types of month indicating means.

8. A continuous catamenial calendar comprising an envelope being open at opposite ends; a slide member movable therethrough; tables of information provided on said slide member, the said tables being arranged so that each side of said slide member contains two distinct tables, the said two distinct tables being arranged inversely in the direction from top to bottom of the slide member whereby the tables may be used for four types of months according to the number of days in each month; a first series of numbers forming part of each of said tables and representing all of the days of said month; a plurality of superimposed second series of numbers forming part of each of said tables and each representing specific days of a month; a plurality of superimposed numerals provided on said envelope and each representing a different length of menstrual cycle; a plurality of windows formed in said envelope and arranged in relation to said series of numbers so that when a particular day of said first series appears in a first one of said windows indicating the first day of a day of an earlier menstruation, an individual day of said second series will appear on the level of each of said cycle indicating numerals in a second window indicating the first day of a following menstruation according to the specific cycle, and a series of days will appear in a third group of windows on the level of each of said cycle indicating numerals, the latter windows indicating the corresponding period of fertility; and means for indicating the type of month associated with each table, the latter means being provided on said slide member.

9. A continuous catamenial calendar comprising an envelope being open at opposite ends; a slide member movable therethrough; tables of information provided on said slide member, the said tables being arranged so that each side of said slide member contains two distinct tables, the said two distinct tables being arranged inversely in the direction from top to bottom of the slide member whereby the tables may be used for four types of months according to the number of days in each month; a first series of numbers forming part of said tables and representing all of the days of said month; a plurality of superimposed second series of numbers forming part of said tables and each representing specific days of a month; a plurality of superimposed numerals provided on said envelope and each representing a different length of menstrual cycle; a plurality of windows formed in said envelope and arranged in relation to said series of numbers so that when a particular day of said first series appears in a first one of said windows indicating the first day of an earlier menstruation, an individual day of said second series will appear on the level of each of said cycle indicating numerals in a second window indicating the first day of a following menstruation according to the specific cycle, and a series of days will appear in a third group of windows on the level of each of said cycle indicating numerals, the latter windows indicating the corresponding period of fertility; means for indicating the type of month associated with each table, the latter means being provided on said slide mem-

9

ber; and a recess provided in said envelope for making visible said type of month indicating means.
